SEDIMENT REMOVAL DEVICE

Thomas R. Smith, Newton, Iowa, assignor to The Maytag Company, Newton, Iowa, a corporation of Delaware

Application May 28, 1956, Serial No. 587,718

6 Claims. (Cl. 68—23)

This invention relates to an automatic washing machine of the vertical axis type in which an upstanding perforate clothes receptacle or tub is rotated relative to a nonrotatable outer tub closely encompassing that clothes receptacle. In this type of washing machine sand or heavy sediment shaken loose from clothing within the clothes receptacle during the first agitation period of the washing cycle passes through the inner perforate clothes receptacle and settles at the bottom of the outer imperforate tub prior to being flushed from that outer tub during the centrifugal extraction operation following the agitation period.

In the operation of such a machine it has been found that the sand and heavy sediment shaken loose from the clothing within the clothes receptacle is normally deposited rather uniformly on the inside surface of the bottom wall of the outer tub during the agitation period. However, during the subsequent centrifugal extraction period when the washing fluid is pumped from the machine to flush away the sand and sediment, not all of the sand and sediment has always been flushed thoroughly from the machine during that operation. This insufficient flushing action has been attributed to the spiral fluid currents circulating between the bottom walls of the clothes receptacle and the outer tub during the centrifuging operation when the clothes receptacle is rotated relative to the outer tub. These fluid currents reverse their direction near the axis of rotation of the clothes receptacle and near the periphery of that receptacle causing the heavier particles in these fluid currents to settle out at these two reversal points. Since the inside periphery of the outer tub is more vigorously flushed by movement of the rotating fluid than is the central area, that peripheral gutter area is flushed more thoroughly than the central area which receives a ringlike deposit around the axis of the revolute clothes receptacle drive shaft.

It is therefore a purpose of this invention to prevent sand or heavy sediment from being deposited in this central zone or other areas of the outer tub of the type washing machine described. This is accomplished in this invention by placing a baffle plate between the perforate clothes receptacle and the outer imperforate tub with that baffle plate covering the drain port leading from the tub. The outer periphery of the baffle plate is sealed and fastened to the inner side wall of the outer tub while the radial edges of that baffle plate are so shaped to cooperate with the bottom wall of the outer tub to form an effluent channel communicating with the tub drain at one end and provided with a throat at its opposite end in the region of the axis of rotation of the clothes receptacle. With this construction the sand settles in much the same manner during the agitation period as it does without the benefit of the baffle plate but once the receptacle is rotated, a major portion of the water and sand is removed from the tub through this channel so that the central area is quite vigorously flushed to scour the sand and sediment away from the central zone and eliminate the problem of sediment deposits in that area. The de-

2

pending side flanges of the baffle plate are provided with openings over the peripheral gutter area of the outer tub so that a smaller portion of the water and sand circulating around the inner periphery of the outer tub is permitted to pass through these openings and scour the inner periphery of that tub member prior to passing through the tub drain port.

In the accompanying drawings:

Figure 1 is a side elevation, partially broken away, 10 showing a washing machine of the vertical axis type incorporating my invention;

Figure 2 is a sectional view taken on line 2—2 of Figure 1 showing the positioning of the baffle plate at the lower portion of the outer tub;

Figure 3 is a fragmentary sectional view taken on line 3—3 of Figure 2;

Figure 4 is a perspective view of the baffle plate which is placed between the inner clothes receptacle and the outer imperforate tub;

Figure 5 is an enlarged fragmentary view of the central portion of the tub structure of the washing machine shown in Figure 1;

Figure 6 is a diagrammatic view of a tub assembly 25 without a baffle plate and showing the normal sediment deposit pattern produced during the agitation period of the operational cycle;

Figure 7 is a diagrammatic view similar to that of Figure 6 showing the sediment deposit pattern formed during the centrifugal extraction operation and indicating 30 generally the fluid current paths causing such sediment deposits; and

Figure 8 is a diagrammatic view of the construction shown in Figure 3 and illustrating the various paths taken by the fluid in its exit from the outer tub resulting in the 35 desired scouring action of the improved tub assembly.

In the accompanying drawings there is shown a base frame 10 mounted on adjustable feet 11 and provided with a supporting dome 12 rising out of a centrally located depression 13 in base frame 10. Dome 12 serves 40 as a mounting for a drive assembly 14 such as that disclosed in the John D. Goodlaxson application, Serial No. 505,231, filed May 2, 1955, and assigned to the same assignee as that of the instant application.

Base frame member 10 also supports the up-ended reversible motor 15 and the water pump 16 which, like drive assembly 14, is driven by motor 15 through belt 17 on the under side of base frame 10. Numeral 19 designates the groove of pulley 18 which serves as the input member for the drive assembly 14.

50 Cabinet 21, attached to and enclosing base frame 10 together with the drive and tub assemblies supported thereby, is provided at its upper end with a depending annular flange 22 defining an access opening into the washing machine apparatus which is normally covered by access door 24.

In Figure 1 it can be seen that dome 12 in base frame 10 is provided with friction pads 26 at its periphery adjacent the opening 27 in its uppermost portion. An umbrella-like support member 28 rests on these friction pads 60 26 and is provided with three equally spaced ears 29 for three centering springs 31 which are fastened to brackets 32 connected to base frame 10. This arrangement centers support member 28 on dome 12 and restrains it from rotation relative to base frame 10.

65 Threaded into the umbrella support member 28 is a member 34 of substantially frusto-conical configuration which serves as a housing for drive assembly 14 of the previously identified Goodlaxson application Serial No. 505,231. Housing member 34 cooperates with umbrella support member 28 by gripping the outer race of a thrust bearing 35 which is provided with a tapered inner race. Mating with and seated in this tapered inner race of bearing

ing 35 is the spin tube or shaft 37 which journals a power shaft 38 also extending into the drive assembly 14. With this construction all weight placed on the spin tube 37, housing 34 and on umbrella member 28 may be used to an advantage to provide ample frictional forces between umbrella member 28 and the friction pads 26 for dampening nutational movements of the shafts 37 and 38 relative to dome 12 while permitting rotational movement of spin tube 37 in thrust bearing 35.

While the details of the Goodlaxson assembly forming the basis of the previously identified application Serial No. 505,231 are not essential to the construction of the instant invention, its operation can be briefly explained for environmental purposes. Upon energization of motor 15 in a direction to rotate pulley 18 in a counterclockwise direction as viewed from the bottom of Figure 1, power shaft 38 is rotated in this same direction while spin shaft 37 is held against rotation by appropriate braking mechanism within housing 34. Upon the reversal of motor 15, spin shaft 37 is released for rotation to allow shafts 37 and 38 to be spun in unison in a clockwise direction.

With the drive and support constructions set forth above, it can be seen that shafts 37 and 38 may be selectively rotated as determined by the direction of rotation imparted to pulley 18 while permitting their nutation about a vertical axis at all times. In the washing machine illustrated in the accompanying drawings, shafts 37 and 38 nutate on a point determined by the intersection of the vertical axis of rotation with a horizontal plane bisecting groove 19 of pulley 18.

Now with reference to the tub assembly, it will be noted that umbrella support member 28 is provided with three recessed upstanding lugs 41 spaced equally from each other and alternately around member 28 with respect to the three ears 29. While not entirely obvious from Figure 1, it will be apparent from this description that there are three lugs 41 spaced 120° from each other each of which is 60° removed from an adjacent ear 29. Fastened within the recessed lugs 41 by connectors 42 are three tub brace members 43 which are, in this embodiment, of channel-like cross section. Brace members 43 extend outwardly and upwardly from umbrella support member 28 to join the non-rotatable imperforate outer tub 44 through tub connectors 45 to form an inverted tripod support for tub 44. The tub 44 is provided with a bottom wall 47 in which is formed a C-shaped gutter 48 having its lowermost portion converging into the drain outlet 49 which in turn communicates with the water pump 16 through the flexible drain hose 51.

The non-rotatable outer tub 44 is provided with a removable crown 52 which permits removal of the rotatable inner clothes receptacle or tub 53 nested within tub 44. Clothes receptacle 53 has a perforate bottom wall 54 and a perforate cylindrical side wall 55 which carries a concrete inertia ring 56 at its uppermost end. A conventional oscillating type agitator 57 is mounted within the inner tub or basket 53 to provide the proper agitation of fabrics placed within the tub assembly thus formed.

In order to drive agitator 57 during the agitation cycle and receptacle 53 during the fluid extraction cycle, the following connections to the drive assembly 14 are provided. Spin tube 37, extending into drive assembly 14, carries at its upper end the lower gear case cover 58 which in turn is bolted to the upper gear case cover 59 carrying counterweight 61 which balances the conventional motion converting unit housed by covers 58 and 59 and driven by power shaft 38.

In Figure 5 the upper gear case cover 59 is shown provided with a mounting stem 64 extending upwardly in a coaxial relationship to spin shaft 37 with which it forms a unitary extension. (The structure not shown to the left of the centerline of agitator shaft 57 in Figure 5 is symmetrical to that shown to the right of that centerline in

that figure.) Mounting stem 64 carries a bearing spacer sleeve 65 which rotates with mounting stem 64 and has its lower end abutting shoulder 66 on the gear case cover 59. Rotation of mounting stem 64 produces a relative rotation between the spacer sleeve 65 and a sintered bronze bushing 67 which journals sleeve 65 and which is pressed into the self aligning outer bearing sleeve 68 to which the rubber sleeve 69 is molded. The lower portion of rubber sleeve 69 defines an oil reservoir 70 which carries wicking 71 in contact with the sintered bushing 67 to provide the latter member with lubricant at all times. Rubber sleeve 69 fits into a centrally located opening formed by the upstanding flange 72 in the bottom tub wall 47 to allow the bearing structure just described to align itself with the mounting stem 64.

Flange 72 in wall 47 is encircled by a boot seal 73 which has its lower end clamped around flange 72 and its upper end provided with a carbon nose seal ring 74. Spring 75 within the boot seal 73 urges nose ring 74 upwardly against a smooth sealing surface provided by the annulus 76 depending from the flanged tub carrier member 77 which is threaded onto mounting stem 64 in abutting relationship to the upper end of spacer sleeve 65. This sealing engagement between ring 74 and annulus 76 provides a water tight seal for the mounting stem 64 while permitting relative movements to take place between the inner tub 53 and the outer tub 44. However, if fluids do seep between sealing ring 74 and annulus 76, they will flow downwardly through the vertical drain ports formed between upstanding flange 72 and the rubber sleeve 69 by means of the grooves 78 located about the upper portion of the latter member as indicated generally in Figure 5.

Referring now to the means for connecting the inner tub or receptacle 53 to the mounting stem 64, it will be noted that the flange 79 of tub carrier 77 is substantially of frusto-conical cross section with a slight radius being formed in its peripheral portion to form a non-linear taper and to provide a supporting seat for the inner tub 53. Tub 53 in turn is formed with an apertured reentrant portion 81 located in the central portion of its bottom wall 54 and formed with substantially the same configuration as the tub mounting flange 79.

This reentrant portion 81 is provided with centrally located inwardly directed horizontal flange 82 which strengthens the circular opening through which carrier 77 protrudes. Since, in actual construction of this tub assembly, inner tub 53 is porcelain enamelled while carrier 77 is formed of aluminum, a cork gasket 83 is cemented on the periphery of flange 79 to provide a water-tight seal and to assure a more uniform unit loading between these parts. Gasket 83 also provides a better frictional engagement between carrier 77 and tub 53 to prevent relative movement between these parts during the operation of the machine incorporating this construction.

Clothes receptacle 53 is wedged against flange 79 as shown generally in Figures 1 and 5. These figures show clamp washer 84 as having a flanged central apertured portion with a body tapered to produce a contour similar to that of reentrant portion 81. The periphery of washer 84 defines a rolled edge which facilitates removal of washer 84 from tub 53 and prevents its gouging the surface of tub member once the tub mounting is assembled.

The large nut 85 threaded on the upper portion of carrier 77 is tightened onto the latter member so as to transmit forces produced by such a tightening action through the centrally located horizontal flanged portion of washer 84 and then into reentrant portion 81 through the tapered body portion of the washer 84. With nut 85 tightened against clamp washer 84 receptacle 53 becomes a unitary assembly with mounting stem 64 and spin shaft 38.

Now with reference to the drive to agitator 57, that agitator member is splined to the upper end of agitator

shaft 87 which receives its rocking movements from the conventional motion converting unit housed between the gear housing covers 58 and 59 and driven by the proper shaft 38. Agitator shaft 87 is journaled in bearing 88 which is seated in the recessed upper end of mounting stem 64. Collar 89, pinned to shaft 87, prevents downward movement of shaft 87 in an axial direction.

Upon rotation of drive assembly pulley 18 by motor 15 in a counterclockwise direction as viewed from the bottom of Figure 1, spin shaft 37 will be braked by mechanism within assembly 14 while power shaft 38 will cause agitator shaft 87 to oscillate agitator 57 within tub 53 in a conventional manner during the agitation periods. Upon reversal of motor 15 during the centrifugal extraction periods, pulley 18 will drive shafts 37 and 38 in unison to extract fluids from damp fabrics within the revoluble receptacle 53 by means of the connection existing between tub 53 and spin shaft 37. While mounting stem 64 may move slightly in the self-aligning bearing structure within flange 72 to produce relative movement between tub 53 and carrier 77 during the centrifugal extraction period, the flexible boot seal 73 will maintain a fluid tight seal with annulus 76 at all times.

During the agitation periods the conventional oscillatory movement of agitator 57 effects the desired separation of impurities from soiled garments agitated in the washing fluid within the clothes receptacle 53. Some of these impurities go into solution or into suspension with the washing fluid while other heavier types of impurities, such as sand, gravitate into tub 44 through the perforate bottom wall 54 and perforate side wall 55 of inner tub 53. Once these heavier particles enter tub 44, it is desirable that they remain in that outer tub during the remainder of the agitation period and then be completely flushed from that outer tub at the beginning of the following spin or centrifugal extraction period when receptacle 53 is rotated.

In practice, without the benefit of the sand baffle plate structure forming the crux of this invention, some of these sand particles have not always been completely flushed from tub 44 during the centrifugal extraction period as desired. Instead, these residual sand particles have passed through the perforate bottom wall 54 of clothes receptacle 53 and have been deposited rather uniformly over the sloping tub bottom wall 47 while accumulating to a somewhat greater degree in gutter 48 during the agitation period as shown at A in the diagrammatic sectional view of Figure 6 which represents a tub assembly not equipped with a sand baffle plate structure. During the centrifugal extraction period following the agitation period the rotation of the clothes receptacle 53 relative to tub 44 caused the water currents to spiral around tub 44 beneath the perforate bottom wall 54 to trace the paths generally shown in the diagrammatic view of Figure 7. As apparent from Figure 7 these spiraling currents traced a path beneath the receptacle bottom wall 54 toward the rotational axis of receptacle 53 at B before reversing toward the peripheral gutter area at C where flow again was reversed. While other current flows were produced, these spiral currents produced the greatest sand deposit problems since the current flow indicated beneath receptacle 53 in Figure 7 caused the sand to settle out at the reversal points B and C. While rotational and centrifugal forces acted on sand particles at point C to reduce possibilities of sedimentation at this point, the flushing action at point B was much less than at point C and was insufficient to achieve a complete scouring of that central area. This resulted in the formation of a ring around the boot seal 73 even after the complete washing operation had been completed. This sediment ring, while being difficult to remove during the centrifugal extraction periods, sometimes recirculated within the recep-

tacle 53 to contaminate subsequent loads of fabrics. In addition, the accumulation of these abrasive particles could harm seal 73 over a period of time.

To prevent such sand and sediment deposits within the tub assembly shown in the accompanying figures, a quadrant baffle plate 90 is positioned between the tub walls 54 and 47 and is generally centered over the drain outlet 49. Its segmental periphery is bolted or otherwise fixed to the inner surface of the cylindrical side wall of tub 44 and is sealed to that side wall by means of gasket 91. Baffle plate 90 is provided with downturned leading and trailing edges 92 and 93, respectively, with reference to the water flow past plate 90 during the centrifugal extraction periods. While the trailing edge 93 is downturned from its periphery to the centrally located upturned edge 95 terminating a short distance from boot seal 73, the leading edge 92 is cut away at 96 over gutter 48 to permit the circulating washing fluid to sweep that gutter area clean. The downturned edges 92 and 93 conform to the contour of tub bottom 47 except over the gutter area and beneath the centrally located upturned edge 95.

In operation, during the agitation periods, when movement of agitator 57 separates the impurities from fabrics contained within receptacle 53 the sediment can settle in

substantially the same uniform pattern as that shown in Figure 6 since the entire tub bottom is thoroughly scoured during the subsequent spin periods. Once the clothes receptacle 53 begins to rotate in the centrifugal extraction operation, its counterclockwise rotation, as viewed in Figures 3 and 8, rotates the entire body of water within the tub assembly in a similar fashion. The rotating body of water then has two major paths of escape from tub 44 as it is pumped from that tub by pump 16. The first of these is defined by the throat formed by upturned edge 95 with a tub wall 47 and the leading and trailing edges 92 and 93 while the second is defined by the gutter 48 and the cut out portion 96. These paths are designated by the arrows of Figure 8. While there may not be a fluid tight seal between the downturned edge 93 and gutter 48, the rotational forces of water reduce the amount of fluid passing into drain 49 in that direction.

Due to the size of the opening beneath edge 95 in comparison to the opening formed by the cut-away portion 96, the suction produced by pump 16 beneath plate 90 draws most of the fluid past the central portion under edge 95 to purge this central area of any sand accumulated in that region while the rotation of the receptacle 53 sweeps the remaining portion of the bottom wall 47 free of any other sediment and allows it to pass along gutter 48 past the cut-away portion 96 and into drain 49. The purging action taking place above and below plate 90 and over the tub bottom wall 47 as shown by the curved arrows of Figure 8 flushes the area between receptacle 53 and tub 44 to eliminate the sediment problem illustrated by the diagrammatic drawing of Figure 7.

Since the theory of operation of this construction depends upon the positioning of the mouth of the fluid channel connected to the tub assembly drain, it will be appreciated that while the illustrated construction represents the preferred embodiment of this invention, it need not be limited to the use of a quadrant baffle plate and does not represent the only satisfactory construction which may be made within the spirit of this invention to achieve the desired purging flow pattern for flushing the tub assembly free from any sand or heavy sediment.

I claim:

1. In a washing machine, a tub adapted to receive fluid and having a bottom wall provided with a drain outlet near the periphery thereof, a revoluble clothes receptacle nested within said tub and having a perforate bottom wall spaced from said tub bottom wall to separate sediment particles from fabrics placed within said receptacle, a baffle plate affixed to said tub and extending from a position over said drain outlet toward the center area of said tub, said baffle plate cooperating with said tub bottom

7
wall to define an effluent channel for said tub open in said central area and extending from said central area to said drain outlet, and pump means communicating with said drain outlet for generating a suction within said channel to scour said central area free of sediment particles deposited on said bottom wall.

2. In a washing machine, a tub adapted to receive fluid and having a bottom wall provided with a drain outlet near the periphery thereof, a perforate clothes receptacle nested within said tub and spaced therefrom to separate sediment particles from clothes placed within said receptacle, a baffle plate positioned between said tub and said receptacle, said baffle plate having a segmental portion placed over the drain outlet and sealed to said tub and having side walls contacting said tub and cooperating therewith to define an effluent passageway having one end thereof leading to said drain outlet and an opposite open end spaced inwardly from the periphery of said tub, and means for creating a suction within said passageway for flushing accumulated sediment particles from within said tub by way of said passageway.

3. In a washing machine, a tub adapted to receive fluid and having a bottom wall provided with a drain outlet near the periphery thereof, a revolute clothes receptacle nested within said tub and having a perforate bottom wall spaced from said tub bottom wall to separate sediment particles from fabrics placed within said receptacle, a baffle plate positioned between said bottom walls and covering said drain outlet, said baffle plate having a segmental portion fixed and sealed to said tub and having downturned sides contacting said tub bottom wall and cooperating therewith to define an effluent passageway for fluid and sediment flushed through said drain outlet, said baffle plate further including an upturned flange defining an intake to said passageway adjacent the rotational axis of said receptacle, and means for creating a suction within said passageway for flushing fluid and accumulated sediment particles from said tub through said passageway.

4. In a washing machine, a tub having a bottom wall, a drain outlet in said tub, a perforate clothes receptacle nested within and spaced from said tub to separate sediment particles from clothes placed within said clothes receptacle, revolute shaft means connected to said receptacle and extending through said tub bottom wall for rotation of said receptacle within said tub, a member positioned between said tub and said receptacle, said member being connected to said tub adjacent said drain outlet and extending from a position over said drain outlet inwardly toward said shaft means to cooperate with said tub in forming an effluent passageway having an inlet opening adjacent said shaft means for removal of fluids from said tub during the rotation of said clothes receptacle by said shaft means, and means for applying a suction to said drain outlet for scouring said tub free of sediment particles accumulated on said tub bottom wall adjacent said shaft means.

5. In a washing machine, a tub adapted to contain washing fluid and having a cylindrical side wall and a bottom wall joined to said side wall, a drain outlet in said tub adjacent the junction of said tub walls, a clothes receptacle nested within said tub and having a perforate bottom wall spaced from said tub bottom wall to separate sediment particles from fabrics placed within said clothes receptacle, revolute shaft means connected to said clothes receptacle and extending through said bottom wall for rotation of said receptacle within said tub, a fluid deflector member connected to said tub and positioned over said drain outlet between said tub and said receptacle, said deflector having marginal portions depending toward said tub bottom wall to form with said tub a water passageway having one end opening toward said shaft means and an opposite end abutting said side wall over said drain outlet, and pump means for creating a suction in said drain outlet for channeling fluid through said passageway and out said drain outlet during the rotation of said basket by said shaft means to scour said tub bottom wall free of accumulated sediment particles.

6. In a washing machine, a tub adapted to contain washing fluid and having a cylindrical side wall and a bottom wall joined to said side wall, a drain outlet in said tub adjacent the junction of said tub walls, a clothes receptacle nested within said tub and having a perforate bottom wall spaced from said tub bottom wall to separate particles from fabrics placed within said clothes receptacle, revolute shaft means connected to said clothes receptacle and extending through said tub bottom wall for rotation of said receptacle within said tub, a fluid deflector member connected to said tub and positioned over said drain outlet between said tub and said receptacle, said deflector having marginal portions depending toward said tub bottom wall to form a water passageway having one end opening toward said shaft means and an opposite end abutting said side wall over said tub outlet, said one end providing the primary fluid intake into said passageway, an auxiliary fluid intake opening in one of said marginal portions providing a secondary flow path into said passageway, and pump means for creating a suction in said drain outlet for channeling fluid through said passageway and out said drain outlet during rotation of said basket by said shaft means to scour said tub bottom wall free of accumulated sediment particles.
